Application August 5, 1954, Serial No. 31,750

Term of patent 14 years

(Cl. D68—1)

FIG. 2.

FIG. 1.

FIG. 3.

Fig. 1 is a front view of a building siding panel showing my new design;

Fig. 2 is a vertical section taken approximately in the plane of the line 2—2 of Fig. 1; and

Fig. 3 is a horizontal section taken approximately in the plane of the line 3—3 of Fig. 1.

The strippling on the drawing indicates contrasting colored areas.

I claim:

The ornamental design for a building siding panel, substantially as shown and described.
